To all whom it may concern:

Be it known that I, SYDNEY STARKEY, a citizen of the United States, residing at East Liverpool, in the county of Columbiana, State of Ohio, have invented a certain new and Original Design for Vases, Urns, &c.; and I do hereby declare the following to be a full, clear, and exact description of the invention, such as will enable others skilled in the art to which it appertains to make and use the same.

My invention relates to a new and original design for vases or similar articles, as shown in the accompanying drawings, in which—

15 Figure 1 is a front elevation of a vase or similar article, illustrating my invention. Fig. 2 is a perspective view of the invention, showing its application to an ewer or similar article.

As shown in the accompanying drawings, the base of the neck is provided with a rim *a*. The head is surmounted by a hat *A*, of 25 the style commonly worn by General George Washington, the ends of the same being formed to provide spouts.

The article is provided with a handle *B*, placed on the rear side. 30

Having thus described my invention, what I claim, and desire to secure by Letters Patent, is—
